Attorney

UNITED STATES PATENT OFFICE.

SAMUEL T. CAVETT, OF EVANSVILLE, INDIANA.

VEHICLE-AXLE.

SPECIFICATION forming part of Letters Patent No. 296,523, dated April 8, 1884.

Application filed September 13, 1883. (No model.)

To all whom it may concern:

Be it known that I, SAMUEL T. CAVETT, a citizen of the United States of America, residing at Evansville, in the county of Vanderburgh and State of Indiana, have invented certain new and useful Improvements in Axle-Trees; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to that class of vehicle-axles which are composed of two sections which revolve and have the wheels permanently fixed thereto; and it also relates to the bearings for such axles. The objects of the invention are to construct axles of this class in such manner as to secure a light draft, to combine durability and simplicity of construction with efficiency of operation, to enable a vehicle to be adjusted to either wide or narrow gage, and to enable the bearings to be lubricated without taking off the wheels or lifting the axles.

The invention consists in certain novel constructions and combinations of devices, which will be fully understood from the following particular description, in connection with the accompanying drawings, in which—

Figure 1 is a view in rear elevation of an axle constructed and mounted in bearings attached to a bolster, according to my invention. Fig. 2 is a section of the coupling-box and sleeve with portions of the axle. Fig. 3 is a perspective view of one of the axle-boxes. Fig. 4 is a view of the axle-sections; and Fig. 5 is a front view of one of the axle-boxes.

The letter A indicates a bolster, having axle-bearing boxes B B, secured to its opposite ends by clips c c c c.

D and D' are two sections of a revolving axle, having intermediate journals, d d, on each side of which are screw-threads, with which are engaged adjustable shoulder-bands e e. On the outer end of each axle-section is a spindle, d', having a screw-threaded tip to receive a nut. On these spindles the hubs of the wheels are to be placed and firmly clamped between the nuts and the outer shoulder-

bands, these outer shoulder-bands being adjustable, as also are the inner bands. The intermediate journals are to be placed in the bearing-boxes. The inner end of the axle-section D is screw-threaded and screwed into a cylindrical coupling-box, F, which is screw-threaded for only a part of its length, the other portion being smooth, to receive loosely the smooth inner end or journal of the other axle-section, D'. In the smooth portion of the coupling-box is formed a slot, s, to admit oil or other lubricating material, and over the coupling-box fits a sleeve, S, which also has a slot, s', for the passage of lubricating material. The sleeve is secured to the box by a set-screw, t. The sleeve is normally turned to such a position that the slots s and s' will not be in line, and the slot s in the coupling-box is thus closed by the sleeve; but when it is desired to lubricate the box and inner end journal of the axle-section D', the sleeve is released by loosening the set-screw and turned to bring the two slots in line, so that the lubricating material may be passed through them both, after which the sleeve is turned and secured in position to close the slot s and prevent the lubricating material from escaping. The coupling-box F being adjustable, and the shoulder-bands of the axle-sections being also adjustable, it is obvious that the complete axle may be adjusted to give the vehicle a wider or narrower gage, as desired. Below the bolster are brace eyes or loops through which the axle-sections pass on each side of the coupling-box. These brace eyes or loops being formed on the ends of bolts which are passed through the bolster and secured by nuts, they serve to counteract the leverage of the axle-sections, which might otherwise deleteriously strain the bearing-boxes when a vehicle is heavily loaded.

By reference to Fig. 5 it will be seen that the bearing-box B has a rear aperture, b, formed by notches cut in the edges of its upper and lower bearing-pieces. This aperture is for the purpose of admitting lubricating material, and above it is hinged a grease-cup, G, which is adapted to be moved down and cover it, and contain a supply of lubricating material, which will thus be gradually fed into the box and to the intermediate journal of the axle-section. The cup is provided on its up-

per edge with perforated lugs *g*, which fit between two perforated ears projecting from the upper bearing-piece, so that the cup may be held closed by a suitable pin passing through 5 said ears and lug.

By means of the aperture *b* and the grease-cup *G*, I am able to keep my axle-bearings constantly lubricated, and there is never any necessity for removing the wheels or axle-sections for lubricating purposes.

Having now fully described my invention, I wish it to be understood that it may be applied to all kinds of wheeled vehicles, and either as a rear or forward axle; and, further, 15 that I reserve to myself the right to make such alterations in the various parts as may contribute to the more efficient carrying out of my invention, while not departing from the essential principle thereof.

20 What I claim is—

1. The combination, with the two axle-sections, of the coupling-box, secured to the inner end of one of said sections, and receiving the inner end of the other section loosely, substantially as described.

2. The combination, with the two axle-sections and the coupling-box fixed to the inner end of one section and receiving the inner end of the other section loosely, and provided with 30 the lubricating slot or opening, of the adjustable sleeve fitting upon said coupling-box and

provided with a lubricating-slot, and means for holding and releasing said sleeve, to permit the rotation of the same, substantially as described.

3. The combination, with the bolster and bearing-boxes secured thereto, of the two axle-sections, provided with intermediate journals, arranged in said bearing-boxes, suspended in loops depending from the bolster, and having 40 their inner ends loosely coupled to revolve independently of each other, substantially as described.

4. The combination, with the bolster, its lubricating bearing-boxes, and the loosely-coupled axle-sections, having intermediate journals in said bearing-boxes, of the brace eyes or loops secured to the bolster and embracing the inner portions of the axle-sections, respectively, substantially as and for the purpose set forth.

45 5. The combination, with the bearing-boxes having apertures, as described, of the hinged grease-caps, adapted to cover said apertures, substantially as set forth.

In testimony whereof I affix my signature, in presence of two witnesses.

SAMUEL T. CAVETT.
